TOY HORSE

Chub Morgan, Palo Alto, Calif.

Application December 9, 1948, Serial No. 64,351

2 Claims. (Cl. 280—1.195)

1

This invention relates to a toy horse of the motivated rocking horse type wherein a rider propels the horse with combined movements of the body and limbs, and in particular a horse mounted on a three wheel frame with the forward end pivotally mounted on the frame and with the rear end connected to an eccentric crank shaft forming the rear axle and also to an actuating lever pivotally mounted in the frame and having pedals on the forward end.

The purpose of this invention is to provide a toy horse that is propelled by a combination of body and limb actions.

In the usual toy horse that is propelled by the rider the power required to motivate the horse particularly up even a slight incline is too great for the average child and the child stands up on the pedals in an effort to increase the propelling force. With this thought in mind this invention contemplates a toy horse in which increased power may be applied to the wheels by the weight of the body of a rider by sitting on the back or saddle wherein the force from the weight of the body is applied directly to the axle of the wheels.

The object of this invention is, therefore, to provide means for pivotally mounting the body of a toy horse on a frame carried on wheels so that the forward end of the body is pivoted at the forward end of the frame and the leverage by which the weight of the body of a rider is applied to the driving wheels is extended to the full length of the horse.

Another object of the invention is to provide a toy horse adapted to be propelled by a rider wherein the propelling force is derived from the weight of the rider through the body of the horse, and pedals are provided for elevating the body of the horse.

A further object of the invention is to provide a toy horse that is propelled by a combination of forces from the weight of a rider and from pedals, which is of a simple and economical construction.

With these and other objects and advantages in view the invention consists of the new and novel combination, construction, and arrangement of parts as hereinafter more fully described, set forth in the claims appended hereto, and disclosed in the accompanying drawings, forming part hereof, wherein:

Figure 1 is a view showing a side elevation of the toy horse.

Figure 2 is a plan view of the horse.

Figure 3 is a cross section through the horse, taken on line 3—3 of Figure 1.

2

Figure 4 is a similar section taken on line 4—4 of Figure 1.

Figure 5 is a detail showing the mounting of the front wheel with the forward part of the body of the horse shown in section, and with part broken away.

Figure 6 is a detail showing on an enlarged scale, an end view of the clip and plate shown in Figure 5 for connecting the body of the horse to the rear axle.

Referring now to the drawings wherein like reference characters denote corresponding parts the toy horse of this invention includes a frame 10 having a yoke with arms 11 and 12 at the rear and a hub 13 at the front, a body 14, pedals 15 and 16, a front wheel 17, and rear wheels 18 and 19.

The body is hinged to the frame through a clip 20 at the forward end of the body which is pivotally connected to a plate 21 by a pin 22. The body is provided with a head 23 which has handle bars 24 and 25 at the sides and the head is fixedly mounted on a vertically disposed steering pin 26 which is journaled in the forward end of the body, and the lower end of the steering pin is connected to the upper end of a stem of a yoke 27 in which the front wheel 17 is mounted on a shaft 28, by a flexible shaft 29.

The rear wheels are carried by an axle 30 which has an offset crank 31 therein that is connected to the under side of the rear of the body by a bar 32, the upper end of which is pivotally attached to a clip 33 on the body. The lower end of the bar 32 is provided with a yoke 34 that is held over the crank of the axle by a pin 35, and the axle is mounted in hubs 36 and 37 at the lower ends of the arms 11 and 12 of the yoke at the rear of the frame.

The pedals 15 and 16 are carried by a lever 38 that is pivotally mounted in a clip 39 by a pin 40 and the rear end of the lever is attached to a link 41 by a pin 42 that extends through a socket 43 at the lower end of the link. The upper end of the link is pivotally attached to a clip 44 on the under side of the body by a pin 45. The pedals are mounted on the ends of a bar 46 that is attached to the lever 38 and gussets 47 and 48 are provided to rigidly support the bar.

The body is provided with a saddle 55 and front legs 56 and 57 extend downward at the front and rear legs 58 and 59 are provided at the rear. A friction washer 60 may also be provided under the neck, as shown in Figure 5, if desired.

With the parts arranged in this manner it will be noted that a downward push on the pedals

will elevate the rear of the body and as the crank passes over the center the weight of the body on the saddle will drive the crank downward and propel the toy forward, and with coordination of the movements the toy may be propelled at a reasonable speed and with considerable power.

It will be understood that modifications may be made in the design and arrangement of the parts without departing from the spirit of the invention.

What is claimed is:

1. In a self propelled toy horse, the combination which comprises a frame having a longitudinally disposed centrally positioned bar having a yoke extended from one end and a vertically positioned hub on the other, a crank shaft journaled in the yoke, wheels mounted on the extended ends of the crank shaft, a front wheel yoke having a vertically disposed stem extended upwardly therefrom and journaled in the hub on the forward end of the centrally positioned bar, a clip extended downwardly from the connection between the end of the centrally positioned bar and yoke in which the rear wheels are carried, a lever pivotally mounted on the clip with one end extended forwardly and downwardly and the other extended upwardly and rearwardly, foot pedals positioned on the forward end of the lever, a link pivotally connected to the rear end of the lever, a link connected to an offset section of the crank shaft, a body having legs and a tail pivotally connected at spaced points to the said links of the lever and crank shaft respectively, a vertically disposed pin extended through the forward part of the said body, a head pivotally connected to the body by the vertically disposed pin, handles on the head, a flexible shaft connecting the lower end of the pin on which the head is positioned to the stem of the yoke in which the front wheel is mounted, and a pair of coacting clips mounted on the lower side of the forward end of the body and on the forward end of the longitudi-

nally disposed bar, respectively for pivotally mounting the body on the bar.

2. In a rider propelled toy horse, the combination which comprises a supporting frame having a front wheel and rear wheels, a body carried by and positioned above the frame, means pivotally connecting the forward end of the body to the frame, a yoke pivotally mounted in the forward end of the frame, means journaling said front wheel in the lower end of the yoke, a steering pin journaled in the forward end of the body, a head carried by the upper end of said steering pin, a flexible shaft connecting the front wheel yoke to the steering pin, said flexible shaft compensating for the upward and downward movement of the body, a rear axle journaled in the frame and on the ends of which the rear wheels are carried, said rear axle having an offset crank therein, a bar connecting said offset crank of the rear axle to the rear part of the body, a lever pivotally mounted in the frame, a link connecting one end of the lever to the body at a point spaced ahead of the point where the bar on the offset crank of the rear axle is connected to the body, pedals on the opposite end of the lever whereby downward force on the pedals elevates the rear end of the body and draws the offset crank section of the rear axle upwardly, and means by which the head may be turned to steer the horse.
